ROOM AIR CONDITIONER

Wendell H. Webster, Albion, Mich., assignor to McGraw-Edison Company, Milwaukee, Wis., a corporation of Delaware

Filed June 3, 1957, Ser. No. 663,135

7 Claims. (Cl. 62—427)

This invention relates to an air conditioning unit of the type usually mounted in a window for the purpose of cooling and introducing into a room recirculated room air, or a mixture of room and outside air, and for further exhausting room air to the outside when desired. In particular, the invention pertains to damper means for controlling the circulation of air through the unit while it is carrying on any of the above mentioned functions.

A general object of the present invention is to provide an air conditioning unit whose parts are so arranged and related as to result in minimal overall dimensions for a given thermal capacity.

A further and more specific object of this invention is to reduce the space requirements of and to reduce the number of dampers for controlling air circulation through the unit by employing a rotary disk damper that occupies little more space than the usual sheet metal partition walls which divide a unit into compartments.

A further object of this invention is to provide damper means that may be controlled from a single station for selecting any one of the air circulating functions mentioned above.

Still another object of the invention, in its preferred form, is the provision of a damper that cooperates with a perforated bulkhead or partition wall to control air flow on the intake and exhaust sides of a centrifugal type room air circulating fan and between compartments of the unit.

Other more specific objects and advantages will appear from time to time throughout the course of the specification.

A more explicit description of the invention will now be set forth in conjunction with the drawing in which:

Fig. 1 is a front elevation view, with parts removed and broken away, of a window mounted type air conditioning unit incorporating the present invention and showing the rotary disk damper adjusted for closing the ports interconnecting front and rear compartments and thereby effecting cooling and recirculating of room air only;

Fig. 2 is a side view, partly in section, taken on a line corresponding with 2—2 in Fig. 1;

Fig. 3 is a sectional view, with parts broken away, taken through the back of the circulating fan scroll chamber on a line corresponding with 3—3 of Fig. 2 showing the damper adjusted in correspondence with Fig. 1 so that the unit cools and recirculates room air;

Fig. 4 is similar to Fig. 3 except that it shows the damper adjusted for admixing fresh outside air into the stream of air being recirculated and cooled; and,

Fig. 5 shows the damper adjusted for exhausting a portion of room air to the outside in addition to recirculating the remainder in the room.

The present invention may be applied to any conventional self-contained room air conditioning unit. In the instant case it is illustrated in connection with an air conditioning unit whose profile is particularly thin and compact, design effort being concentrated upon the prob-

2

lem of reducing overhang of the unit beyond the frame of the window in which it is mounted.

The unit illustrated in Fig. 1 has its outer decorative housing removed in order to show that, aside from the invention, it comprises the usual components such as a metal base 1 which supports a functional sheet metal enclosure 2. The unit includes a refrigeration compressor 3 whose operative connections to a heat absorbing evaporator coil 4 and a heat dissipating condenser coil 5 have been eliminated for the sake of clarity.

The sheet metal enclosure 2 is divided into two principal compartments, including a cooling or heat absorbing, front compartment 6 and a heat dissipating, rear compartment 7, by means of a substantially vertical partition wall or bulkhead 8, see Fig. 2. A portion 8' of partition wall 8 is inclined forwardly so that the heat dissipating compartment can accommodate the large condensing coil 5. The rear or dissipating compartment 7 is occupied by a fan motor 9 that is supported on a bracket 10 resting on metal base 1. The rear shaft end 11 of motor 9 carries a one-piece condenser fan 14, of the propeller type, adapted to draw air into compartment 7 through a plurality of downwardly directed inlet louvers 15. Fan 14 draws fresh outside air through louvers 15 and directs it upwardly through condenser coil 5 whereupon it is discharged to the outside ambient through a plurality of outlet louvers 16 which direct the outgoing air in a strata above that of the incoming fresh air. Both compartments 6 and 7 are closed at their ends by suitable fiber board or metal sheets, for example.

Viewing Fig. 2 it will be seen that the cooling compartment 6 is provided with a centrifugal fan 17 of the double inlet type. The front inlet 18 of the centrifugal fan is aligned with an opening 19 through a sheet metal wall 20, and the rear inlet 21 is partially occupied by spokes 22 provided with a hub 23 for fastening the fan to the front end motor shaft 12. In practice the number of spokes 22 may exceed the four shown, but some of them have been eliminated here in order to avoid obscuring air circulating ports in partition wall 8.

Centrifugal fan 17 is located closely between vertical partition walls 8 and 20 which combine with an arcuately shaped sheet metal bottom 26 to define a scroll chamber 25 surrounding the centrifugal fan 17. The scroll chamber opens at its top, see Figs. 1 and 2, and into a discharge chamber 27 which conducts air through cooling coil 4, a filter 28 and out into the room being cooled. Cooling coil 4 is supported on a horizontal plate member 29 forwardly of fan 17, to define a room air plenum chamber 30 in conjunction with the base 1. The front of the plenum chamber 30 is provided with a filter 31 which removes air borne impurities from the front intake of the fan 17 as filter 28 removes it from the air discharged by the fan.

In Fig. 1 it will be seen that there is provided a space 32 of approximately equal height to the scroll chamber and set off by a vertical wall 34 for the purpose of accommodating a pushbutton station 33, a temperature selector 35 and other electrical control elements, not shown.

Attention is now invited to the novel damper arrangement for placing compartments 6 and 7 in communication on either the intake or exhaust sides of centrifugal fan 17, or for isolating the two compartments from each other.

Referring to Fig. 3, it will be seen that vertical partition wall 8 is provided with intake ports 38 and exhaust ports 40. Noise reducing and sealing felt 43, which is visible through the above named ports 38 and 40 in Fig. 3, is attached by gluing or other suitable means to a rotary damper disk 44 located to the rear of partition wall 8, see Fig. 2. Referring again to Fig. 1, and looking endwise into fan 17, it will be observed that intake

ports 38, in wall 8, are aligned with the interior or suction side of the centrifugal fan. The exhaust ports 40, however, are located in wall 8 on the exhaust side of centrifugal fan 17 and outside of its outer periphery as defined by the tips of blades 45.

It is evident that when intake ports 38 are open as in Fig. 4, fresh air will be drawn from rear compartment 7 through ports 38, 39 and into the rear inlet 21 of fan 17 after which it will be expelled through cooling coil 4 and into the room.

Accordingly, when inlet ports 38 are closed and exhaust ports 40 are open as in Fig. 5, air that has been drawn from the room through the front inlet 18 of fan 17 will be pressurized in scroll chamber 25 and partially exhausted through exhaust ports 40 into compartment 7, after which the air is forced into the outside ambient through condenser coil 5 under the further influence of condenser fan 14. The remainder of the air is cooled and recirculated to the room.

When both the intake ports 38 and exhaust ports 40 are closed as in Fig. 3, air is drawn from the room through plenum chamber 30 and front fan inlet 18, and recirculated to the room under the influence of the centrifugal fan which forces it through cooling coil 4.

The outline of damper disk 44 is clearly apparent in Figs. 3 to 5 where it is seen to constitute a single piece sheet metal member that is radially enlarged around a portion of its periphery to provide a region in which at least one exhaust port 41 may be perforated for registering with one corresponding exhaust port 40 in partition wall 8 when the damper resides in its Fig. 5 position at which time the enlarged region also clears and opens the other exhaust port 40. At a lesser radius, and in alignment with the rear inlet 21 of centrifugal fan 17, the damper disk 44 is provided with four intake ports 39 which may be registered with corresponding intake ports as in Fig. 4.

The margin of damper disk 44 is provided with a series of stamped gear teeth 46 that are enmeshed with a coacting closed-end pinion or gear 47. Gear 47 is pinned through its hub to an operating shaft 48 that extends forwardly to a control station in front of the unit. Shaft 48 may be journaled in several places such as where it passes through partition walls 8 and 20, and the back of a channel 49 that extends laterally across the front of the unit. A manual shaft control knob 50 that is accessible from the front of the unit points to indexing designations, not shown, but inscribed on the front of the unit in order that the operator may select the various damper positions as illustrated in Figs. 3, 4 and 5.

Damper control shaft 48 is surrounded by a compression spring 51 which is interposed between partition wall 8 and a fixed washer 52 in such manner that shaft 48 is constantly biased toward the front of the unit, or to the left when viewed in Fig. 2. The closed end face 53 of gear 47 has a small notch 54 that normally receives a detent projection 55 which is pressed in the sheet metal from the front toward the rear of the partition wall 8. The detent projection and notch tend to remain engaged under the influence of compression spring 51 so as to give the operator a sensory indication that the damper is or has arrived at a position where it has closed both sets of intake and exhaust ports 38, 39 and 40, 41. The detent projection and its cooperating notch tend to disengage easily if manual control knob 50 is pressed rearwardly or if it is merely rotated with slight additional force to initiate movement of the damper in either a clockwise or counterclockwise direction from the Fig. 3 position to respective Fig. 5 and Fig. 4 positions.

Damper disk 44 may be supported for rotation on partition wall 8 in any suitable manner. In this case the damper 44 is provided with a central clearance hole 56 for admitting motor shaft 12 therethrough. Air leakage along the shaft is prohibited by the felt 43 being perforated by a hole that is slightly under the shaft diam-

eter so as to secure a wiping fit between the shaft and felt. The partition wall 8 has a large hole 58 whose edges act as a bearing for tabs or ears 59 that are pierced forwardly from damper disk 44 from the margin of its hole 56. Ears 59 pass tightly through appropriate slots in the felt and they are bent radially outward on the front of partition wall 8 so that the damper cannot withdraw from hole 58 in the partition wall and so the damper may rotate on the ears.

In the commercial unit, bearing area between the damper 8 and its bearing hole 58 is improved by inserting the body portion of a collar not shown, in the nature of a shallow flanged cup, through hole 58 so that the flange portion overlays the hole margin. The cup portion extends backwardly into hole 58 and provides an annular bearing surface about the interior thereof. The ears 59 pass through the collar and hold the damper against the wall. This detail has been omitted from the drawing because it is not indispensable to understanding the significance of the novel damper means and how it directs the air in various paths through the unit.

The operational mode of an air conditioning unit provided with the novel damper means will now be summarized. Under operating conditions electrically driven refrigerating compressor 3 maintains evaporator coil 4 at low temperatures for absorbing heat from room air circulating through it. Condenser coil 5 is adapted to liberate heat to the outside air that is circulated through it by propeller fan 14.

When the damper 44 is positioned as in Fig. 3, there is no communication between front compartment 6 and rear compartment 7. Accordingly, rotation of centrifugal fan 17 by fan motor 9 causes air to be drawn from the room into front fan inlet 18 after which the fan forces it upwardly through chamber 27, through cooling coil 4 and into the room again.

When the damper is moved counterclockwise to its Fig. 4 position by rotating manual control knob 50 clockwise, exhaust ports 40, 41 remain closed but intake ports 39, in the damper, and ports 38 in the partition wall 8 register. This connects rear inlet 21 of the fan to the rear compartment 7 so that fresh air, which has been forced into compartment 7 by the propeller fan 14 may be drawn into the centrifugal fan rear inlet 21 and mixed with further air drawn from the room through the front inlet 18 and then jointly forced into the room through cooling coil 4.

When the damper is adjusted as in Fig. 5, only exhaust ports 40, 41 are in registry. Under these circumstances, part of the room air that is drawn through front fan inlet 18 for being recirculated is diverted at the bottom of the scroll chamber 25, at the discharge side of the centrifugal fan, through the exhaust ports 40, 41, whereupon it is added to the stream of air passing through condenser coil 5 and finally ejected to the outside ambient.

It has been disclosed how all desired air circulating functions of an air conditioner can be controlled from a single station by means of a damper that occupies a minimum amount of space in conjunction with a partition wall that produces a particular compartmentation of the unit. It will be understood, however, that the damper may be located in different places in differently compartmented units and that it may be modified insofar as its configuration and number of ports is concerned. Likewise, it may now be evident to those practicing the art that the damper may be actuated by means other than the gear drive suggested herein. Accordingly, this disclosure is intended to be illustrative rather than limiting, for the invention may be variously embodied and its scope is to be interpreted by the claims which follow.

It is claimed:

1. A self-contained room air conditioner including a housing and a partition wall separating said housing into a room communicating heat absorbing compartment and a heat dissipating compartment, a fan in said absorbing

compartment adapted to impel the flow of air therethrough and discharge the same into the room being cooled, said partition wall being exposed to the intake side of said fan and provided with an intake port adjacent said intake side of said fan and further provided with an exhaust port, a substantially planar rotary damper adjacent said partition wall and having a port registerable with the intake port in said wall, and means for rotating said damper for selectively placing said ports in registry and thereby interconnecting said compartments for drawing air from the second compartment axially through the fan and into the room being cooled.

2. A self-contained room air conditioner including a housing and a partition wall separating said housing into a room communicating heat absorbing compartment and a heat dissipating compartment, a fan in said absorbing compartment adapted to impel the flow of air therethrough and discharge the same into the room being cooled, said partition wall being exposed to the intake side of said fan and provided with an exhaust port adjacent the region of discharge from said fan and further provided with an intake port, a substantially planar rotary damper adjacent said partition wall and having an exhaust port registerable with the exhaust port in said wall, and means for rotating said damper for selectively placing said exhaust ports in registry and thereby interconnecting said compartments for discharging air from said first compartment into said second compartment.

3. A self-contained room air conditioner including a housing and a partition wall separating said housing into a room communicating heat absorbing compartment and a heat dissipating compartment, a fan in said absorbing compartment adapted to impel the flow of air therethrough and discharge the same into the room being cooled, said partition wall being adjacent an end of said fan and provided with an intake port and an exhaust port lying respectively inside and outside the periphery of said fan, a substantially planar rotary damper adjacent said partition wall and having ports registerable with corresponding intake and exhaust ports in said wall, and means for rotating said damper for selectively placing corresponding intake ports in registry and thereby interconnecting said compartments for drawing air from the second compartment axially into the fan and discharging it into said first compartment, or placing corresponding exhaust ports in registry for discharging air from outside the periphery of said fan from said first compartment into said second compartment.

4. A self-contained room air conditioner including a housing and a partition wall separating said housing into heat absorbing and heat dissipating compartments each having an opening communicating with the space being conditioned and the outside air respectively, a double inlet centrifugal fan in said absorbing compartment disposed with one of its inlet sides presented to the room opening and the other inlet side presented to said partition wall, a cooling coil disposed in said absorbing compartment in the discharge path of said fan, a condenser coil in said dissipating compartment and also a condenser fan adapted to draw air into the last named compartment and expel the same through said condenser coil and said outside opening, said partition wall having an intake port lying within the periphery of said centrifugal fan and adjacent one inlet side thereof, a substantially planar rotary damper adjacent said partition wall and having a port registerable with the intake port in said wall, and means operatively coupled with said damper for rotating the same and selectively placing said ports in registry whereby fresh air may be drawn from the heat dissipating compartment into one inlet side and mixed with air from the other inlet side of said centrifugal fan and discharged into the room.

5. A self-contained room air conditioner including a housing and a partition wall separating said housing into heat absorbing and heat dissipating compartments each

having an opening communicating with the space being conditioned and the outside air respectively, a double inlet centrifugal fan in said absorbing compartment disposed with one of its inlet sides presented to the room opening and the other inlet side presented to said partition wall, a cooling coil disposed in said absorbing compartment in the discharge path of said fan, a condenser coil in said dissipating compartment and also a condenser fan adapted to draw air into the last named compartment and expell the same through said condenser coil and said outside opening, said partition wall having an exhaust port lying outside the periphery of said centrifugal fan and in the region of discharge from said fan, a substantially planar rotary damper adjacent said partition wall and having exhaust port means registerable with the exhaust port in said wall, and means operatively coupled with said damper for rotating the same and selectively placing said ports in registry and thereby interconnecting said compartments for discharging a portion of room air from said centrifugal fan into said heat dissipating compartment.

6. A self-contained room air conditioner including a housing and a partition wall separating said housing into heat absorbing and heat dissipating compartments each having an opening communicating with the space being conditioned and the outside air respectively, a double inlet centrifugal fan in said absorbing compartment disposed with one of its inlet sides presented to the room opening and the other inlet side presented to said partition wall, a cooling coil disposed in said absorbing compartment in the discharge path of said fan, a condenser coil in said dissipating compartment and also a condenser fan adapted to draw air into the last named compartment and expel the same through said condenser coil and said outside opening, said partition wall having an intake port adjacent said inlet end of said centrifugal fan and lying inside the periphery of said fan and said wall having an exhaust port lying outside of the fan periphery, a substantially planar rotary damper adjacent said partition wall and having ports registerable with corresponding intake and exhaust ports in said wall, and means for rotating said damper for selectively registering intake ports to draw outside air from said dissipating compartment through said other inlet side of said centrifugal fan, or for registering exhaust ports to impel air through said centrifugal fan from the room into said second compartment.

7. A self-contained room air conditioner including a housing having front and rear openings which are presented to the room being conditioned and the outside ambient air respectively, a partition wall separating said housing into front and rear compartments, a motor driven double inlet centrifugal fan in said front compartment adapted to draw in air through one inlet from the room being conditioned and to discharge air from its outer periphery, said well being provided with intake ports communicating with the interior of said fan through its other inlet, said wall further being provided with exhaust ports communicating with the discharge side of said fan, a substantially planar rotary damper adjacent said wall and having intake and exhaust ports selectively registerable with said corresponding first named ports, means for rotating said damper for registering corresponding ports with each other, said means including gear means on said damper and cooperating gear means engaged therewith, whereby rotation of said last named gear means to a first angular position registers said intake ports for adding air from the rear compartment to air in said front compartment, and rotation to a second angular position registers said exhaust ports for expelling air from said front compartment to the rear compartment, and rotation to a third angular position closes all ports for recirculating air through said front compartment only.
